(57) **CLAIM**

The ornamental design for a car multifunctional storage bag, as shown and described.

DESCRIPTION

FIG. 1 is a front perspective view of a car multifunctional storage bag, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof, with the top in an open configuration; and,

FIG. 9 is a front perspective view thereof; with the front pocket shown open.

The broken lines representing stitching are part of the claimed design.
